Application July 16, 1936, Serial No. 90,860

2 Claims. (Cl. 181—31)

This invention relates to amplifiers and has particular reference to so-called microphone amplifiers or boosters especially adapted for amplifying the voice currents of a portable hearing aid device.

Heretofore, microphone amplifiers for portable hearing aid devices having the usual clamped diaphragm had a limited output in both energy and tone range, due largely to poor diaphragm damping, which introduced distortion of a large and detrimental value. These former devices also had undesirable frequency discrimination within the usable tone range and were difficult to manufacture, so much so that unless extreme care and precision were exercised in their manufacture, the response characteristics of apparently identical devices would vary widely.

In accordance with the present invention, a microphone type of amplifier especially adapted for hearing aid devices is provided, which is simple in construction, has an extended tone range, acts as though damped without corresponding loss of output efficiency, has a high amplification and output, and can be manufactured in large quantities with excellent uniformity.

The invention comprises a casing of small size, preferably adapted to be carried by and directly electrically connected to the usual battery packet, and containing the carbon granule microphone cell electrically connected to the air- or bone-conduction receiver, the carbon granules being in operative electromechanical contact with the specially-mounted diaphragm of an electromagnetic actuating means, actuated by the microphone or transmitter, for mechanically rearranging the energized mass of carbon granules to continuously change its conductivity in accordance with the fluctuations in the voice currents flowing through the actuating means, whereby these currents are amplified in the well-known manner of operation of carbon granule microphone amplifiers.

The diaphragm, loaded by the attraction of the electromagnetic actuating means, is distorted from its normal free shape jointly by this attraction and by the clamping means therefor, the latter positively dishing the diaphragm in a direction opposite to the direction of attraction of the electromagnetic actuating means, while the former opposes this distortion by flexing the center of the diaphragm in the said direction, so that the diaphragm is doubly curved in cross-section. This distortion of the diaphragm is preferably obtained by properly tapering the seat upon which the diaphragm is clamped at

its periphery, although this distortion may be procured in other ways, such as by forming the clamping ring seat eccentrically with one side lower axially than the other, or by pre-forming the diaphragm to impart a slight dish or crown thereto.

It will be seen that with this arrangement, the amplifier does not depend largely for its response characteristics upon the inherent flexibility or stiffness of the material of the diaphragm, but by virtue of this double distortion, different radial points thereon are placed under different internal tension, affording a degree of restrained flexibility which enables it to vibrate freely at various frequencies and act as though damped, procuring special operating characteristics without output loss. Among these special characteristics is the ability of the diaphragm to change its mass-stiffness ratio at different frequencies, so that it tends to resonate at various frequencies, with the result that the amplifier responds to a broad range of frequencies with uniform results. Also, with this arrangement, the diaphragm acts as though damped at its primary resonance point with little absorption of energy. This effect allows closer adjustment of the air gap to obtain high output sensitivity and efficiency without liability of contact between the diaphragm and the pole faces.

For a more complete understanding of the invention, reference may be had to the accompanying drawing, in which:

Fig. 1 is a side view of the microphone amplifier of this invention with the cover plate of the enclosing casing removed;

Fig. 2 is an enlarged axial section through the amplifier unit as seen along the line 2—2 of Fig. 1;

Fig. 3 is a greatly enlarged and exaggerated view of the novel diaphragm arrangement;

Fig. 4 illustrates a modified form of the diaphragm arrangement; and

Fig. 5 is a conventional wiring diaphragm for a hearing aid device.

Referring to Fig. 1 of the drawing, numeral 10 designates a casing of hard rubber, phenolic resin, or the like, carrying contact prongs 11 which fit into corresponding sockets in a conventional battery packet 12, which is usually connected as is indicated in the circuit diagram of Fig. 5. The several parts of the hearing aid device include the transmitter-microphone 13, an air- or bone-conduction receiver 14, and the microphone amplifier unit 15, having the windings 16 and the microphone 17. Other circuit

arrangements may be utilized according to requirements.

The microphone amplifier unit 15, shown in enlarged section in Fig. 2, includes a tubular housing 18 of conducting material, such as brass, which is closed at one end by a non-conducting disc 19 of porcelain, phenolic resin, or the like, secured in place by screws 20 and carrying the carbon button 21 electrically connected to the external contact 22. This contact 22 connects the microphone 17 in the circuit of receiver 14 by suitable connections with the casing 10.

A clamping ring 23 threaded into the open opposite end of housing 18 cooperates with the seat 24 in housing 18 to clamp the diaphragm 25 in position. A ring of cotton wadding 26 interposed between diaphragm 25 and disc 19 forms with the latter the carbon granule chamber 17 containing the mass of carbon particles 27 of suitable dimensions, either granular in form or comprising carbon balls.

Threaded into the housing 18 is a nonconducting plug 28 of hard rubber, phenolic resin or the like, having secured to its outer face by means of clamp 29 a bar magnet 30 contacting the poles of a pair of windings 16. The faces 31 of the poles lie in close proximity to the armature 32 of diaphragm 25, forming an air gap which is adjustable by screwing plug 28 into or out of housing 18. The terminals of the windings 16 are suitably connected in the hearing aid circuit by means of contacts 33 connected by leads 34 to binding posts 35 on casing 10, as is indicated in Fig. 1.

As shown in exaggerated form in Fig. 3, the seat 24 of housing 18 is chamfered or beveled and the cooperating surface of clamping ring 23 may be flat or similarly chamfered or beveled. The angle A at which the seat 24 is chamfered or beveled depends upon the degree of distortion which is to be imparted thereby to the normally plane diaphragm 25, but for purposes of hearing aid devices the angle A ranges preferably between five minutes and one degree. Accordingly, when the plane diaphragm 25, which is preferably made of phosphor bronze or some other suitable material, is clamped between seat 24 and clamping ring 23, the taper or chamfer of the seat imparts a dish shape to the diaphragm 25, which is opposite to the distortion produced by the magnetic load at the center of the diaphragm by the attractive force of the windings 16 energized by the battery 12 and/or magnet 30. The diaphragm 25 accordingly acquires a sinuous shape in cross section, as is indicated in exaggerated form in Fig. 3, causing different radial portions thereof to be under different degrees of tension in accordance with the double distortion effected jointly by the taper of seat 24 and the magnetic load applied to its center portion by the windings 16. It will be observed that the diaphragm is supported only at its periphery.

As is illustrated in exaggerated form in Fig. 4 the distortion of the diaphragm may also be obtained by forming the seat 24' eccentrically in such a way that one side is axially lower by a small amount B than the opposite side, i. e., the plane of the seat 24' is not normal to the axis of the threads in the housing.

The portion of the seat at the right of Figure 4 is parallel to but spaced below the left hand portion of the seat. Lines drawn radially or transversely of the seat 24' are substantially perpendicular to the axis of the threads in the housing. Thus, when the diaphragm is clamped flatly

against all portions of the seat, it is distorted into a sinuous cross-sectional shape, for the reason that the opposite portions of the seat do not lie in a common plane. The clamping ring 23' is not similarly eccentric so that when it engages the diaphragm 25', the latter is distorted in a manner somewhat similar to that produced with the arrangement illustrated in Fig. 3, that is to say, the diaphragm is forced out of its normal plane condition into a distorted shape which is generally somewhat sinuous, as is indicated in exaggerated form in Fig. 4. With this arrangement different radial portions of the diaphragm are placed under different degrees of tension so that the required results are obtained. Other ways of obtaining this mechanical distortion of the diaphragm may be provided.

Instead of distorting a plane diaphragm in the manner described, the primary distortion can be provided by pre-forming the diaphragm 20 with a slight dish or crown, which, after mounting in the amplifier, is modified by the magnetic attraction into the aforementioned doubly-curved shape.

In operation, the voice currents impressed 25 on the windings 16 of the microphone amplifier of this invention result in vibration of the diaphragm to rearrange the mass of carbon particles 27 to change its conductivity and effect amplification in the well known way. The restrained flexibility of the diaphragm produces an improved response curve due to its double curvature providing different tension at different radial points, which causes it to change its mass-stiffness ratio at different frequencies so that 35 it tends to resonate at various frequencies. Also, with this simple arrangement, all diaphragms made according to production requirements have uniform response characteristics, so that microphone amplifiers embodying these diaphragms 40 may be made in large numbers with uniform success.

While a preferred embodiment of the invention has been illustrated and described herein, it is to be understood that the invention is not limited thereby but is susceptible of changes in form and detail within its scope. Also, while the novel diaphragm arrangement has been described as applied to microphone amplifiers, it may be used with equal facility in microphones, 50 transmitters, receivers, loud-speakers and other acoustical instruments of all kinds without requiring substantial modification. For diaphragms of relatively larger diameters than $\frac{3}{4}$ inch, which is the nominal diameter of the diaphragm of a portable hearing aid amplifier, the angle A varies in accordance with diameter flexibility, and the like. It is also to be understood that the term "diaphragm" employed herein and in the appended claims is not necessarily confined to circular diaphragms except as described, but also comprehends strip diaphragms or reeds.

I claim:

1. In an acoustic device, the combination of a diaphragm, a housing, an inwardly projecting shoulder therein having a surface forming a seat for the edge portions of the said diaphragm, said shoulder having an inner edge portion lying in a plane inclined with respect to an axis, said axis being substantially perpendicular to all lines 65 which are perpendicular to said edge and to lines tangent to said edge and lying in said surface, means for clamping said edge portions flatly against said seat, whereby the diaphragm is distorted into a wavy cross-sectional shape, and 70

an electromagnet associated with said diaphragm for distorting its center portion into a doubly curved shape with the convex surface thereof directed toward said electromagnet.

- 5 2. In an acoustic device, the combination of a circular diaphragm, a housing, an annular inwardly projecting shoulder therein having a surface forming a seat for the edge portions of said diaphragm, said shoulder having an inner edge 10 portion lying in a plane inclined with respect to an axis, said axis being substantially perpen-

dicular to all lines extending radially from said axis and lying in said surface, means for clamping said edge portions flatly against said seat, whereby the diaphragm is distorted into a wavy cross-sectional shape, and an electromagnet associated with said diaphragm for distorting its center portion into a doubly curved shape with the convex surface thereof directed toward said electromagnet.
